UNITED STATES PATENT OFFICE.

JOSEF BRANDSTETTER, OF CHICAGO, ILLINOIS.

AUTOMATIC STOP FOR ELECTRICALLY-DRIVEN PHONOGRAFS.

Application filed November 5, 1927. Serial No. 231,305.

My invention relates to a phonograph attachment for use with a motor-driven phonograph of the type in which the reproducer is carried by a tone arm which moves over a horizontal turntable while the record is being played, and in its general objects aims to provide simple means for rupturing the current-supply circuit to the motor and speedily halting the record when the tone arm reaches a certain position.

Furthermore, my invention provides a simple, cheap and highly compact mechanism for this purpose which can easily be attached to standard types of phonographs and which can readily be adjusted by the user according to the size of the record. It also provides a construction for this purpose in which the electric switch portion is effectively concealed and housed, while both the trip arm and the starting lever are conveniently accessible.

Still further and also more detailed objects will appear from the following specification and from the accompanying drawings, in which

Fig. 1 is a front elevation of an automatic stop embodying my invention, together with a fragmentary vertical section of the tone arm of the phonograph on which the stop is positioned.

Fig. 2 is a plan view of the stop with the trip arm disposed in a vertical position, together with a fragmentary section of the rim of the turntable of the phonograph.

Fig. 3 is a bottom view of the same automatic stop.

Fig. 4 is an enlarged and fragmentary front elevation of the same automatic stop, together with a vertical section through the horizontal part of the phonograph cabinet to which the stop is fastened.

Fig. 5 is a view taken from the bottom of Fig. 4.

Fig. 6 is a vertical section taken along the line 5—5 of Fig. 4.

Fig. 7 is an enlarged vertical section taken along the line 7—7 of Fig. 2, with the parts positioned as they appear during the playing of a record.

Fig. 8 is a section similar to Fig. 7, but taken after the detent has been released so as to actuate the stop.

In the illustrated embodiment, my automatic stop includes a generally flat sheet metal base 1 adapted to be fastened to the top of the horizontal cabinet board 2 with the major portion of this base underhanging the

usual depending rim 3 of the turntable which rotates about a vertical axis. Pivoted intermediate its ends to the base 1, as by a vertical pivot pin 3, is a switch lever 4 which has one arm extending beyond the base and the rim 3, the free end of which arm desirably is formed to afford a handle 5.

The other arm of the switch lever moves over a slot 6 in the base and carries a pin 7 which extends downwardly through this slot into a vertical perforation 8 formed in the cabinet board 2. Secured to the bottom of the base is an insulator 9 which has a vertical notch or recess 10 larger than the slot 6 and underhanging the latter as shown in Fig. 5. Mounted on this insulator at opposite sides of the recess 10 are two wire terminals 11, each of which carries a resilient contact 12. These stationary contacts are spaced from each other and disposed so that they will be simultaneously engaged by a movable contact member (consisting of a metal sleeve 13 carried by the pin 7 and insulated from the latter by an insulating sleeve 14), when the switch lever is swung in one direction by a tensioning spring 15 interposed between this lever and a riser pin 16 fastened to the base.

To hold the switch lever at this end of its travel during the playing of a record (namely, with the movable contact member 13 engaging both of the contacts 11, as shown in Fig. 5) I provide a detent lever of a bell-crank form pivoted by a horizontal pin 17 to a riser web 18 on the base 1. One arm 19 of this detent extends substantially horizontally and has a vertical shoulder 20 normally engaging an edge of the switch lever, as shown in Fig. 7, and a spring 21 continuously urges this lever arm 19 upwardly so as to hold the said shoulder thus disposed. The other and vertical arm 22 of the bell-crank detent lever has an upwardly directed trip arm 23 disposed in extension of it and secured to it through a friction joint 24 which will permit the trip arm to be adjusted in position with respect to the vertical arm 22. This trip arm is disposed in the path of the horizontally swinging tone arm 25 of the phonograph and is adjusted in position according to the size of the record which is being played, so that the trip arm (and hence the detent arm) will be moved in a clockwise direction in Fig. 1 when the tone arm reaches the end of the record.

When the detent lever is thus moved against the resistance of the spring 21, the

shoulder 20 clears the edge of the switch lever 4 and the spring 15 then rotates the switch arm (in a clockwise direction in Fig. 2) until the switch lever 4 is engaged by another 5 vertical shoulder 26 on the detent arm 19, as shown in Fig. 8. This latter shoulder 26 is so positioned that the switch arm will be stopped after the movable contact member 18 has moved away from both of the stationary contacts 12, but before the pin 7 reaches the adjacent end of the slot 6, thereby preventing undue strains on this pin and on its connection to the switch arm. Consequently, 10 the circuit to the motor 27, which is shown 15 diagrammatically in Fig. 3, is immediately opened.

In practice, I preferably mount a brake shoe 28 on the switch arms also and dispose 20 this brake shoe so that it will engage the rim 3 of the turntable of the phonograph when the spring 15 draws the switch arm to its said circuit-opening position, thereby quickly 25 halting both the turntable disk and the motor which is operatively connected to this turntable.

Thus arranged, my automatic stop is highly compact and can easily be attached to standard types of phonographs, since this merely requires the boring of the hole 8 in 30 the cabinet and the fastening of the self-contained stop to the top of this board by screws extending through perforations 30 in the base. When thus attached, the switch is entirely concealed and shielded against contacting 35 with needles or other metal objects which might short-circuit or otherwise damage it. Moreover, the entire stop is quite low in cost of manufacture.

However, I do not wish to be limited to the 40 mounting of both the brake shoe and the movable switch contact on the same lever, nor to other details of the construction and arrangement above described, since many changes might be made without departing either from 45 the spirit of my invention or from the appended claims.

I claim as my invention:

1. An attachment for a phonograph driven by an electric motor and including a tone arm: 50 automatic stop including a switch, a pivoted lever controlling the switch and having the movable contact member of the switch mounted on the lever, spring means continuously tending to move the lever in a switch-opening direction, and a pivoted detent member having an arm disposed in the path of the tone arm and having a detent portion normally engaging the said lever to hold the latter in its switch-closing position, the said detent 55 portion being moved out of its said lever-holding position when the tone arm engages the impact portion.

2. A phonograph stop as per claim 1, in 60 which the detent member also has another portion disposed for engaging the said piv-

oted lever to limit the movement of the latter in the said direction by the spring.

3. An automatic stop for a phonograph driven by an electric motor, comprising a stationary base plate, a switch including a switch lever pivoted to the base plate and a movable contact member carried by the said lever, a spring continuously tending to move the switch lever to its circuit-closing position, a detent lever pivoted to the base plate on an axis transverse of the pivoting axis of the switch lever, the detent arm having a portion normally holding the switch in its circuit-opening position, and an extension arm pivoted to the detent lever through a friction joint, and 70 extending across the path of movement of the tone arm of the phonograph.

4. A phonograph stop as per claim 3, in which the base plate is horizontal, in which the detent lever and the major portion of the switch lever are disposed above the base plate, and in which the switch lever has a portion extending downward through the base plate; the switch having its movable contact member mounted on the said lever portion below 80 the base plate, and the switch also including a stationary contact disposed below the base plate and engaged by the said member when the switch lever is in its circuit-closing position.

5. An automatic stop for a phonograph driven by an electric motor, comprising a pair of spaced and relatively insulated stationary contacts disposed in the motor circuit, a pivotally mounted switch lever, a movable contact member mounted on one arm of the switch lever, a bell-crank detent lever pivotally mounted on an axis transverse of the axis of the switch lever and having a shoulder on one arm normally engaging the other arm of the switch lever to hold the latter in a position in which the movable contact is out of engagement with the stationary contacts; a trip arm mounted on the other arm of the detent lever and extending across the path of the tone arm of the phonograph, whereby the movement of the tone arm during the playing of a record will move the detent lever out of its said switch lever holding disposition; and a spring disposed for moving the switch lever when thus released from the detent, so as to cause the switch lever to move the movable contact into engagement with the stationary contacts.

6. For use with a phonograph having a record-holder driven by an electric motor and a tone arm movable above the record-holder, an automatic stop comprising: a base, a braking member pivoted upon the base and having a friction portion adapted to engage the record holder; a switch including a stationary contact mounted on the base and a removable contact carried by the braking member, the said contacts forming portions of a circuit to the motor, spring means continuously tending to move the braking member to cause 120 125 130

the said friction portion to engage the record and to move the said movable contact into engagement with the stationary contact; and a latching member movably mounted on the 5 base and normally preventing movement of the braking member in the aforesaid direction; the latch member having a portion disposed in the path of the tone arm, whereby engagement of the tone arm with the latching member releases the braking member so as to 10 premit the spring means to move the braking member in the said direction.

7. An attachment for a motor-driven phonograph of the type having a horizontally 15 swinging tone arm, comprising: a horizontal base provided with a slot, a switch lever pivoted to the base on a vertical axis and having on one arm of the lever an extension projecting downwardly through the said slot, insulating means secured to the base below the latter, 20

a pair of spaced contacts mounted on the insulating means at opposite sides of the slot and both in the circuit to the motor, a movable contact member carried by the said extension and adapted to engage both of the said spaced 25 contacts when the switch lever is in one position, a detent movably mounted on the base and disposed for latching the switch lever in its said position, a trip arm associated with the detent and engageable by the tone arm of the phonograph to move the detent out of its 30 said latching disposition; and spring means for moving the switch lever out of its said position when the detent is released, so as to move the movable contact member out of engagement with the said spaced contacts. 35

Signed at Chicago, Illinois, October 31st, 1927.
